[57] **CLAIM**

The ornamental design for a wrist support for use with a keyboard, typewriter or similar article, as shown and described.

DESCRIPTION

FIG. 1 is a perspective view of a wrist support for use with a keyboard, typewriter or similar article showing my new design;

FIG. 2 is a front view in elevation of FIG. 1, as shown with the support member in its higher position;

FIG. 3 is a front view in elevation of FIG. 1 except with the support member shown in its lower position;

FIG. 4 is a right side view in elevation of FIG. 1; and FIG. 5 is a top plan view of FIG. 1.

Fig. 1.

Fig. 2.

Fig. 3.

Fig. 5.
